UNITED STATES PATENT OFFICE.

FREDERICK FRANCIS NYČ, OF KERRVILLE, TEXAS.

FILM DEVELOPING, FIXING, AND WASHING APPARATUS.

1,000,287.

Specification of Letters Patent. Patented Aug. 8, 1911.

Application filed August 22, 1910. Serial No. 578,280.

To all whom it may concern:

Be it known that I, FREDERICK F. NYČ, a citizen of the United States, residing at Kerrville, in the county of Kerr and State 5 of Texas, have invented new and useful Improvements in Film Developing, Fixing, and Washing Apparatus, of which the following is a specification.

This invention relates to photography 10 and particularly to a combined film developing, fixing and washing tank, and the purpose of the same is to furnish a convenient mode of developing, fixing and washing films in a more satisfactory and reliable manner and enabling an operator to 15 obtain the very best results. By using this tank or developing apparatus the dark room becomes merely a place for loading the tank, as all the remaining operations of developing, fixing and washing are effected in the 20 tank.

With this and other objects and advantages in view the invention consists in the construction and arrangement of the several 25 parts which will be more fully hereinafter described and claimed.

In the drawings: Figure 1 is a perspective view of a tank or apparatus embodying the features of the invention and showing 30 the lid or cover removed and part of the co-operating devices exterior of the tank. Fig. 2 is a top plan view of the tank or apparatus showing the cover of the main receptacle removed. Fig. 3 is a diagrammatic sectional elevation in full and dotted lines and illustrating the manner of removing the film 35 from the tank or apparatus. Fig. 4 is a detail elevation of a portion of the film supporting coil.

The tank or apparatus embodies essentially 40 a receptacle or main tank 5, preferably constructed of copper and having a removable lid or cover 6 with an air vent 7 and a Z-shaped funnel 8 also supplied with a removable cover 9. Within the receptacle 45 or main tank 5 is a metal coil 10 and co-operating therewith are clamps 11 which are used to removably secure the film at its extremities to the coil. The tank or apparatus 50 also includes in its equipment a film removing device 12 to facilitate the withdrawal of the film from the receptacle or main tank after it has been subjected to the

developing, fixing and washing operations, the said removing device operating to hold 55 the film in such shape during its withdrawal from the receptacle or tank as to avoid any possible injury to the film and maintaining the parts thereof in such relation as to obviate injury to any part of the film. The 60 Z-shaped funnel 8, which is used as an ingress means for the developing and fixing solutions into the tank and also for the introduction of water to wash the films, is constructed in the particular form specified 65 to prevent light from entering the receptacle or main tank and especially to obviate fogging the film by actinic light. By the use of this form of funnel all the operations necessary to the full development of the 70 film may be performed in daylight without necessity of entering a dark room, the single operation of loading the tank being excepted. It will be observed that the lower end of the funnel 8 connects with the side 75 of the tank 5 adjacent the bottom of the latter for obvious advantageous reasons.

The coil 10 is preferably constructed of copper and has formed therein a plurality of openings 13, see Figs. 3 and 4, and is 80 also preferably crimped as at 14 regularly throughout the length thereof. The openings 13 permit a free circulation of the several liquids introduced into the tank through the coil to facilitate the developing, fixing and 85 washing of the film, and the crimped portions of the coil provide outstanding projections against which the duplex paper at the non-sensitive side of the film has bearing so as to reduce the surface contact of 90 the film relative to the coil as much as possible and also position the film on the coil at a distance from the latter or to provide a space between the outer side of the coil and the non-sensitive side of the film, such 95 position of the film giving the best results in the developing, fixing and washing operations. The coil 10 has a fixed position within the receptacle or main tank 5, and when the film is applied thereover the ends 100 of the said film are removably secured through the medium of the elongated wire clamps 11, the latter simulating hairpins in their contour and formed of resilient wire to set up the necessary binding action on the 105 film and coil extremities. The film when

applied to the coil is unsecured between the ends thereof, as clearly shown by Fig. 2, the clamps 11 having been found sufficient to hold the film in position during the several operations to which it is subjected.

The film removing device 12 consists of an elongated U-shaped wire body 15 from the horizontal member of which a plurality of chains or analogous flexible devices 16 are suspended at intervals and carry clasps 17 at their lower ends, the number of chains or flexible devices and clasps used corresponding to the number of spiral convolutions intersecting one of the diameters of the receptacle or main tank, there being six convolutions as shown and the same number of clasps. It will be understood, however, that the number of convolutions may be varied in accordance with the proportions of the receptacle or main tank and coil, and to accommodate this variation the clasps 17 may be increased. The maximum length of the film removing device 12 is such as to permit the legs 18 thereof to fit over diametrically opposite portions of the receptacle or tank 5, and by this means the clasps 17 are suspended within said receptacle or tank and brought in close relation to the upper edge portions of the film convolutions, care being taken in the application of the clasps to the film that the latter do not engage more than about one-eighth of an inch of the top of the film so that the picture on the film will not be injured.

It is also proposed to heavily nickelplate all parts of the apparatus including the clamps 11 and film removing device 12 to prevent deterioration of the metal by the solutions brought into contact therewith during the several operations of developing and fixing the film. The film to be developed, fixed and washed is inserted in the receptacle or main tank 5 in a dark room, the film being wound about the coil 10 with the duplex paper adjacent to the non-sensitive side of the film in contact with the projections formed by the crimps 14, the sensitive side of the film being outermost, and as hereinbefore explained, the extremities of the film are secured to the coil by pushing the clamps 11 downwardly thereover. After the film is inserted in the tank over the coil, the lid or cover 6 is tightly fitted or placed over the top of the tank or receptacle and the latter may be vented when found necessary through the medium of the air vent 7 which will be normally closed. The main tank or receptacle in its covered condition, and having the film therein is then taken from the dark room and the developing and fixing solutions are introduced through the funnel 8 and likewise at the proper time the film may be washed by introducing a washing liquid into the funnel. After the developing and fixing as well as

the washing operations have been completed the lid or cover 6 is removed and the device 12 is disposed over the receptacle or tank, as shown by Fig. 4, and the clasps 17 are caused to engage upper edge portions of the films. After all of the clasps have been secured to the different portions of the film the clamps 11 are removed and the operator then grasps the horizontal portion of the device 12, as shown by Fig. 3, and withdraws the film from the tank or receptacle. In releasing the film from the device 12 it is conveyed over a basin of water and the clasps are successively detached and the film allowed to drop in the water and may then be dried in the usual manner.

In placing the undeveloped film in the tank or receptacle in the dark room, the film should be held in the left hand with the sensitive side turned away from the operator and the one end of the film, after it has previously been attached to duplex paper, is fastened to the coil, starting from the outermost end of the said coil and progressing toward the center of the tank or receptacle. Previous to the introduction of the film to the tank, it should be observed that the latter is thoroughly cleaned, and in placing the negative in the tank the operator should not permit his hands and fingers to touch the sensitive surface of the film more than is absolutely necessary. It will be understood that any developing and fixing solutions will be used and as the liquids introduced through the funnel into the tank or receptacle will stand at the same level in both the latter and said funnel, the operator will be enabled to readily ascertain when sufficient quantity of either the developing or fixing liquid has been poured into the funnel to effect the operations sought.

What is claimed is:

1. In an apparatus of the class specified, the combination of a main tank having a rigid coil fixed therein for removably receiving an undeveloped film and also provided with a Z-shaped funnel connecting with the side portion thereof, and provided with two elbows and means for closing the tank.

2. In an apparatus of the class specified, a main tank having a film receiving coil mounted therein; the coil being of spiral form and immovably fixed in the tank the coil having outstanding projections, and tubular means having a plurality of angular bends adapted for supplying the interior of the tank with developing, fixing and washing liquids.

3. In an apparatus of the class specified, a main tank having a film receiving spiral coil fixed therein for removably receiving an undeveloped film and provided with a plurality of apertures therethrough at inter-

5
vals, and light excluding means of tubular form having two elbows and adapted for the introduction of developing, fixing and washing liquids into the tank, the light excluding means being secured to the side of the body and communicating with the latter near the bottom of the same.

10
4. In an apparatus of the class specified, a main tank having a coil fixed therein and provided with a plurality of outstanding projections extending vertically thereover and perforations at intervals therein, the perforations being formed in the projections means for closing the tank, and light excluding means adapted for the introduction of developing, fixing and washing liquids into the tank.

15
5. In an apparatus of the class specified, a tank having a removable closure and provided with a liquid introducing light excluding funnel, a spiral coil immovably mounted in the tank for application thereto of a film, and removable clamping devices applied vertically over the upper edge of the coil and

25
movable downwardly over the latter for engaging the extremities of the coil and film.

6. In an apparatus of the class specified, a main tank provided with closure means and a liquid introducing funnel having double angular elbows, and a film holding coil disposed in the tank and crimped at intervals to produce outer projections for engagement by the film.

30
7. In an apparatus of the class specified, a main tank having a film holding coil therein and means for introducing a liquid thereto, and a film removing device consisting of an elongated U-shaped frame to fit over the tank and having a plurality of clasps suspended therefrom to engage different 35
40 portions of the film.

In testimony whereof I have hereunto set my hand in presence of two subscribing witnesses.

FREDERICK FRANCIS NYC.
